(57) **CLAIM**

We claim the ornamental design for a portable computer, as shown and described.

DESCRIPTION

FIG. 1 is a rear perspective view of a portable computer of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is an end view taken along the line 8-8 in FIG. 2;

FIG. 9 is a rear perspective view thereof shown in a slid position; and,

FIG. 10 is a rear perspective view thereof shown in a closed position.

The broken line showing of a portable computer is included for the purpose of illustrating environment only and forms no part of the claimed design. Additionally, the dot-dash broken lines shown adjacent the rear edge of the computer in FIGS. 1, 7 and 10 define the limits of the claimed design.
